Design No. 18,252, dated April 10, 1888.

UNITED STATES PATENT OFFICE.

MINNIE KENT, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,252, dated April 10, 1888.

Application filed February 23, 1888. Serial No. 265,049. Term of patent 3½ years.

To all whom it may concern:

Be it known that I, MINNIE KENT, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made

to up by the pattern will appear.

The design shows a basque and a round walking-skirt. The skirt exhibits a flat double box-plaited drapery upon the front and sides, the middle two plaits reaching to the belt and the plait at either side being overhung at the top by a pannier drapery that displays draping plaits at the top, and a full back drapery descending to the edge of the skirt in jabot and straight fall. The basque exhibits close-

fitting fronts that open above the bust over a narrow-pointed chemisette and lap diagonally below; a close-fitting back that displays an underfolded double box-plait at the end of its center seam and falls in a postilion between pointed side backs; a standing collar, coat-sleeves, and a lapel turning from the front edge of the left front. The lower outline describes a point at the center of the front and a high arch at the sides.

What I claim as my invention, and desire to secure by Letters Patent, is—

The design for a lady's costume, as shown in the engraved prints accompanying this specification.

MINNIE KENT.
